UNITED STATES PATENT OFFICE.

JAMES H. WAGENHORST, OF AKRON, OHIO.

BATTERY-JAR-FORMING MACHINE.

1,338,470.

Specification of Letters Patent. Patented Apr. 27, 1920.

Application filed September 14, 1918. Serial No. 254,088.

To all whom it may concern:

Be it known that I, JAMES H. WAGENHORST, a citizen of the United States, residing at Akron, in the county of Summit and 5 State of Ohio, have invented a certain new and useful Battery-Jar-Forming Machine, of which the following is a specification.

This invention relates to the manufacture of receptacles from sheet material, and more 10 particularly to the making of storage-battery jars from sheets of plastic vulcanizable hard-rubber compound. While attempts have been made to provide molding or forming machines for this work, it is still the 15 general practice, so far as I am aware, to form the jars from sheets of rubber laid on a mandrel and joined at the bottom edges and the side seam by hand labor. My invention has for its object to provide an improved jar-forming device which will eliminate much of the excessive bulk and complication of prior devices intended for the 20 purpose, and which, by dispensing with the need of high skill and the slow operations 25 of hand manufacture, will improve the product and enable it to be made at a reduced cost.

Of the accompanying drawings,

Figure 1 is a vertical longitudinal section of a jar-forming machine embodying 30 my invention, with the work in position.

Fig. 2 is an end elevation.

Fig. 3 is a plan view, with the wrapping box opened out.

Fig. 4 is a vertical transverse section of 35 the machine, showing the partly-formed jar.

Fig. 5 is an enlarged detail cross-section, illustrating the formation of the side seam.

Fig. 6 is a face view of the bottom-press- 40 ing plunger.

Fig. 7 is a plan view showing a modification which constitutes a preferred form of the invention, the machine being closed.

Fig. 8 is an end view thereof.

Fig. 9 is a cross-section on the line 9—9 45 of Fig. 7.

One of the principal features of the invention consists of means such as a series of hinged plates for wrapping the side-forming sheet about a core or mandrel with-

out any relative movement occurring between the plates and the stock. The mandrel is preferably placed in a horizontal position and the hinged plates, when closed, form a box or casing around it. Other features comprise means, preferably located on the hinged plates, for turning the bottom edges of the sheet, means for pressing said edges to form the bottom seams, means for forming and trimming the side seam, a novel 55 mandrel holder and a mode of mounting said holder to swing into and out of operative position.

Referring to Figs. 1 to 6, 10 is a base or frame at one end of which a mandrel-holder 65 11 is pivoted on a horizontal pin 12. 13 is the core or mandrel of the usual prismatic form for making battery jars, having top and bottom faces and four side faces, of which latter two are wide and two are narrow, giving an oblong cross-section. In this case I provide the mandrel along its top edges with a head flange 14 for detachably connecting it with the holder 11 by means of over-hooking plates 15, 16 on the latter, 70 said plates forming a lower horizontal groove and two vertical grooves occupied by the corresponding edges or tenons of the head-flange, whereby a sliding tongue-and-groove interlocked engagement is effected. 75 The pivoting of the holder permits the latter to be swung upward and outward so that the mandrel may occupy an inverted, vertical position when it is to be connected with and disconnected from the holder, and while 80 the bottom-forming sheet of stock is being applied to the mandrel. In this position, an abutment 17 on the back of the mandrel holder is supported on a stop or rest 18 on the base 10. In its operative position, 85 as shown in the drawings, the mandrel is placed horizontally, edgewise, or with its top and bottom faces and its two wider sides vertical, and its two narrower sides horizontal, in order to facilitate the location of 90 the side-forming sheet upon the opened-out wrapping box, and the performance of 95 the various operations upon the work.

The wrapping box 19 comprises five plates 20, 21, 21^a, 22 and 23, connected by 100

four sets of hinges 24, 25, and having a collective width sufficient to inclose the mandrel with an intervening space on all sides equal to the thickness of the jar walls. The 5 lower plate 20 is bolted to the base 10, and the two wider side-forming plates 21, 21^a are provided on their backs with bosses 26 which rest upon supporting members 27 on the base when the box is opened out as in 10 Fig. 3. These three plates coact with the corresponding three sides of the mandrel, while the two terminal plates 22, 23 coact with the fourth side. The plates 22, 23 are provided with over-center tension springs 15 28 attached to pins 29, 30 on said plates and the hinges 24 respectively, for holding these plates under pressure in either their opened-out or their closed positions, their opening movement being limited by the abutting of 20 their rear edge faces against the adjacent edge faces of the plates 21, 21^a as indicated in Fig. 4. When the members of the two pairs of plates 21, 23 and 21^a, 22 are in this relation, the tension of the springs 28 25 permits either pair to be swung as a unit on the lower hinge 24, by grasping the handle 43 or 39 on the corresponding terminal plate; and when the plate 21 or 21^a is stopped by contact of the work with the 30 side of the mandrel, a further exertion of force on the handle causes the terminal plate to swing over on the narrow upper face of the mandrel.

The two terminal plates 22, 23 act as 35 folders for the two ends or margins of the side-forming sheet, and they also form the side seam. On these plates I provide a pair of coacting longitudinal, hardened edge-pieces or blades 31, 32 for forming the 40 seam, said blades having a shearing action to trim off the excess from the overlapping edge of the material.

The left-hand edges of the several folder plates, as viewed in Figs. 1 and 3, are provided 45 with shallow, inwardly-directed flanges 33, 34, 34^a, 35, 36, having concave forming faces, for the purpose of turning the edges of the side-forming sheet around those of the bottom-forming sheet to make 50 the bottom edge seams.

For clamping the four folder-plates 20, 21, 21^a and 22 together in closed position upon the work, I provide a hand-lever 37 hung on a pivot 38 between the arms of 55 a fork 39 which projects from the plate 22, said lever having a hub cam 40 adapted to engage a complementary locking member or keeper 41 on the folder-plate 21, there being an adjustable stop-screw 42 on the cam-lever for limiting the amount of squeezing 60 pressure which may be applied. Plate 23 is not subject to the clamping pressure but is provided with a separate operating handle 43, so that independent pressure may

be applied to the side seam, the amount 65 of this pressure being limited by an adjustable stop-screw 44 whose inner end engages the back of the plate 22.

An important detail consists in locating the axes of the hinges 24, 25 in the planes 70 of the inner faces of the hinged sections, so that these axes coincide with the geometrical corners of the finished jar. By using a wrapping box, especially when provided with this hinge-axis location, all harmful drawing, rolling, buckling and distortion of 75 the stock is avoided, and it becomes possible to make a jar without providing the usual facing-sheets of tin on the stock to reinforce it during manipulation. While I 80 might employ this tin facing where desired to have a polished outer surface on the finished work, it is preferred to dispense therewith on account of the resulting saving in cost of manufacture. 85

45 is the side-forming sheet of material and 46 the bottom-forming sheet. 47, 47 are the deep internal ribs on the bottom of the jar, known as "lugs", for supporting the 90 battery plates, the bottom of the mandrel 13 being recessed in the usual way to receive these lugs.

48 is a head or plunger carried on the end of a rod 49, which is mounted for horizontal sliding movement in bearings 50 on the frame and actuated by a hand-lever 51, the latter being pivoted to said frame at 52, and connected with the head 48 by a pair of links 53, said links and the short arm of the lever constituting a toggle. The 95 forward and rearward movements of the head are limited by stops 54, 55, the former being adjustable. On the edges of the plunger 48 are mounted four forwardly-projecting plates 56 for compressing the inwardly-turned edges 57 of the side-forming sheet 45 which overlap the margins of the bottom-forming sheet 46 to constitute the 100 bottom seams, these presser plates 56 sliding on the edge-turning flanges 33, 34, 34^a, 11 35, 36 of the folder sections. The ends of the presser plates, as well as the ends of the edge-turning flanges when the box is closed, meet so as to form two complete quadrangles. 115

58 is a bottom-pressing and embossing plate slidably mounted on front of the plunger 48 between the plates 56, this plate being yieldingly backed by springs 59 which surround guide-pins 60 attached to said 120 plate and projecting through holes in the plunger 48, the forward motion of plate 58 on the plunger being limited by the heads of the pins. Transverse grooves 61 are formed in the face of the plate 58 opposite the lugs 47 to mold shallow embossed reinforcing and jar-supporting ribs under the lugs 47, these ribs in the finished jar being 125

substantially flush with the members 57 of the corner seams. A light spring 49^a tends to retract the rod 49 and plunger 48, but is overcome by the weight of lever 51 when the latter is placed in the position shown in Fig. 1, with the presser plate 58 resting against the bottom of the work.

The operation of this apparatus is started with the wrapping box 19 opened out flat, as shown in Fig. 3, and the mandrel holder 11 turned up from the position represented in the drawings, so that a core or mandrel 13 engaged therewith by means of the tongue-and-groove connection 14, 15, 16 will occupy an inverted vertical position. In this position, the pieces of raw stock for forming the lugs 47 may be readily inserted in their grooves, and the bottom-forming sheet 46 accurately laid upon and supported by the end of the mandrel. A side-forming sheet cut to the proper size is laid upon the opened-out box 19 and properly registered with the edges thereof, its bottom edge being slightly overlapped upon the edge-turning plates 33, 34, 34^a, 35, 36. The holder 11 and mandrel 13 are then swung down into horizontal operative position, and the plunger 48 is advanced until its presser-plate 58 rests against the work to hold the bottom sheet in place as shown in Fig. 1, the weight of the lever 51 keeping the parts in this position while the side wrapping is performed. Then the free sections 21, 21^a, 22, 23 of the wrapping box, carrying with them the superimposed portions of the side-forming sheet 45, are closed upon the mandrel. First, the two wider side sections 21, 21^a are swung upwardly into position, and then the section 22 is turned over on the upper side of the mandrel and clamped to the section 21 by means of the lever 37, causing a locking engagement of the cam 40 and keeper 41 which produces a pressure upon the work. The final step in the side-folding operation consists in turning the folder section 23 and its corresponding sheet portion over upon the upper face of the mandrel by means of the handle 43 as indicated in Fig. 5, and applying pressure to the side seam formed by the overlapping skived edges of the sheet 45. In all of this wrapping action it will be observed that there is no relative movement between the wrapping means and the stock. The latter can be accurately registered on the wrapping box while said box is opened out, and when the wrapping has taken place, there will be a perfect meeting of the edges of the stock at the side seam, and a proper initiation of the bottom seams by overlapping on the sheet 46. The wrapping action is progressive and avoids the entrapping of air. At the four corners of the bottom edges the coming together of the mitered ends of the turning flanges 33, 34, 34^a, 35,

36 so gathers and pinches the stock that the subsequent compression by the plates 56 thoroughly perfects the seams at these important points. The final closing movement of section 23 causes a shearing action of blade 32 against blade 31, which trims off the excess of material on the outer side of the seam. The location of said seam near the left edge as viewed in Fig. 5, making section 23 narrower than section 22, enables the air to be pressed out from under the narrow flap and reduces the amount of pressure required in making the side seam. By the exertion of pressure upon the hand-lever 51, the plunger 48 is then further advanced, carrying with it the yieldingly-mounted plate 58 which compresses and embosses the bottom sheet 46 as previously described, and consolidates it with the lugs 47, while the seam-pressing plates 56 on the plunger compresses the inwardly-turned edges 57 of the side sheet 45 and perfect the bottom seams, the inward flow of the material parallel to the bottom being limited by the edge faces of the plate 58, so that these corner seams are fully confined on all sides during the compressing action. The wrapping box is then unclamped and opened out, and the mandrel 13, with the formed jar thereon, is swung upwardly into vertical position. It may then be removed by sliding it from the holder 11 and the jar vulcanized in the usual manner while still on the mandrel. A fresh mandrel is then substituted and the foregoing operations repeated.

It will be seen that this apparatus is very simple and easy to operate, and may be constructed at relatively small cost compared to prior machines intended for a similar purpose. The product is superior to the average of hand-made jars and the saving of expense over hand labor is very considerable.

Various changes of embodiment are within the scope of the invention.

I have shown certain modifications in Figs. 7 to 9, wherein the same reference characters, in general, represent the same or similar parts as in Figs. 1 to 6. The most important difference consists in an altered arrangement of the operating mechanism for the terminal folder-plates or sections 22, 23, my principal object in this connection being to inter-engage these sections in the act of forming the side seam, and thus minimize the effect of the personal equation of the operator which enters to some extent when the final pressure is exerted on one of these folder-sections independently of the other. The folder-section 22 in this case has only latching engagement with the section 21, by means of a pair of arms 61 with hooked extremities 62 taking over the extended hinge pintles 25^a which connect

the sections 21 and 23, there being stop-screws 63 on these arms to engage the pintles and limit the closing movement of section 22. One of the arms has a handle extension 5 64 for manipulating said folder section 22. The folder section 23 is formed with a pair of arms 65 between which is pivoted, on a hinge pin 66, a clamping lever 67 formed with a hub-cam 68 adapted to engage 10 a complementary locking member or keeper 69 on the back of the folder section 22, there being a stop-screw 70 on the cam-lever for engagement with said folder section to limit the clamping movement of the lever. An 15 over-center spring 71 extending between a pin 72 on the clamping lever and a pin 73 on one of the arms 65 holds the clamping lever in either its retracted or its projected position with reference to the folder section 20 23. A stop 74 on the clamping lever engages a projection 75 on said holder section to limit the retracting movement. The over-center springs 28 of Figs. 1 to 6 are in this case omitted.

25 The folding-over of the terminal flaps and the formation of the side seam are effected in this modified embodiment by first turning the folder section 22 into the position indicated in Figs. 6, 7 and 8 and latching it to the folder section 21 by means of the members 62 and 25^a. Then the handle of the clamping lever 67 is grasped and the folder section 23 turned over nearly into the position shown in Fig. 9, a continuation of this 30 turning movement causing the cam 68 on said lever to interlock with the folder section 22 and clamp all parts of the folder firmly upon the work, the seam being compressed and trimmed by the final movement of 35 folder section 23 which squeezes out and pinches off the small strip 76 of excess rubber stock shown in said view.

Other changes of a minor character consist in a slight difference in the shape and 40 arrangement of the folder sections 22, 23 and their hardened plates 31, 32 over the previously-described embodiment, as is apparent in the drawings, the modified arrangement providing sections of equal width 45 which meet in the middle; also the provision of separate face-plates 77 on the folder sections 21, 21^a, secured by screws 78 and backed by shims 79 for the purpose of gagging the width of the clearance spaces occurring 50 the side walls of the jar; together with a crank handle 80 for conveniently manipulating the pivoted mandrel-holder 11.

I claim:

1. In a jar-forming machine, the combination of a mandrel, and means for progressively wrapping a sheet of stock about said mandrel without relative movement between said means and the stock.
2. In a jar-forming machine, the combination of a prismatic mandrel, and a wrap- 65

ping box composed of sections hinged together at points corresponding to the side edges or corners of said mandrel.

3. In a jar-forming machine, the combination of a prismatic mandrel, and a 70 wrapping box composed of sections complementary to the sides of said mandrel and hinged together on axes in the planes of the inner faces of the sections corresponding to the corner edges of the work. 75

4. In a jar-forming machine, the combination of a mandrel having a substantially horizontal operative position, and a sectional wrapping box adapted to support the whole of a sheet of stock horizontally in an 80 opened-out condition and progressively wrap the same about said mandrel.

5. In a jar-forming machine, the combination of a prismatic mandrel, means for operatively supporting the same with its 85 length horizontal, and means adapted to fold a plastic sheet of material about said mandrel and form a longitudinal seam at the meeting edges of said sheet on the upper side of the mandrel. 90

6. In a jar-forming machine, the combination of a mandrel, and a wrapping box composed of hinged sections adapted to enclose said mandrel, the adjacent edges of the two terminal sections acting as seam-forming members for a sheet of plastic material. 95

7. In a jar-forming machine, the combination of a prismatic mandrel, and a wrapping box composed of intermediate and 100 terminal sections hinged together on axes corresponding to the side edges of the mandrel, the two terminal sections meeting between the edges of one of the mandrel sides.

8. In a jar-forming machine, the combination of a mandrel having four sides and top and bottom faces, and a hinged wrapping box composed of three sections complementary to three of the sides of said mandrel and two terminal sections complementary to 110 the fourth side.

9. In a jar-forming machine, the combination of a mandrel, and a box composed of hinged sections for wrapping a sheet of stock about said mandrel, said box including terminal sections adapted to form and trim the longitudinal side seam at the ends of said sheet. 115

10. In a jar-forming machine, the combination of a mandrel, and a pair of hinged folding members operating against one side of said mandrel and having coacting seam-forming trimming blades on their adjacent edges. 120

11. In a jar-forming machine, the combination of a mandrel, a box comprising hinged sections for wrapping a sheet of stock about said mandrel, and means for latching non-adjacent sections of said box together upon the work. 125 130

12. In a jar-forming machine, the combination of a mandrel, a box comprising hinged sections for progressively wrapping a sheet of stock about said mandrel, without relative movement between said sections and the work, and means for clamping together, in operative relation to the work, the two terminal sections of said box. 70
13. In a jar-forming machine, the combination of a four-sided mandrel, a box composed of five hinged sections for wrapping a sheet of stock about said mandrel, and clamping means connecting the two terminal sections for drawing all of said sections against the work. 75
14. In a jar-forming machine, the combination of a mandrel, a box composed of sections hinged together at the lateral side corners of the mandrel and adapted completely to surround said mandrel for wrapping a sheet of stock about the latter, and a single clamping means for pressing said sections together upon the work. 80
15. In a jar-forming machine, the combination of a four-sided mandrel, a wrapping box composed of three intermediate and two terminal sections hinged together, means for interlatching one of said terminal sections and the intermediate section to which the other terminal section is hinged, and interlocking clamping members for drawing the two terminal sections together against the work. 85
16. In a jar-forming machine, the combination of a mandrel adapted to receive a bottom-forming sheet of stock on its end face and side-forming stock on its side faces, and a hinged series of edge-turning members working across the bottom edges of the side faces. 90
17. In a jar-forming machine, the combination of a mandrel, and a wrapping box composed of hinged sections for inclosing the sides of said mandrel and provided with bottom-edge-turning members. 95
18. In a jar-forming machine, the combination of a mandrel adapted to receive a bottom-forming sheet of stock on its end face and side-forming stock on its side faces, edge-turning members working across the bottom edges of said faces and forming an inclosure in their projected positions, and bottom-seam-compressing means working within said inclosure. 100
19. In a jar-forming machine, the combination of a mandrel, a hinged series of turning members working across the bottom edges of the mandrel sides and adapted to form an inclosure in their projected positions, and bottom-seam-compressing means working endwise of the mandrel within said inclosure. 105
20. In a jar-forming machine, the combination of a mandrel, a wrapping box composed of hinged sections for inclosing the sides of said mandrel and provided with seam-turning members working across the bottom edges of the mandrel sides, and bottom-seam-compressing means working endwise of the mandrel between said members. 110
21. In a jar-forming machine, the combination of a mandrel, bottom-seam-turning means coacting therewith, bottom-seam-compressing means movable endwise of the mandrel and forming an inclosure, and a bottom presser working within said inclosure. 115
22. In a jar-forming machine, the combination of a mandrel, bottom-seam-turning means coacting therewith, a plunger movable endwise of the mandrel and having bottom-seam-compressing means around its edges, and a yieldingly-projected bottom presser plate mounted on the face of said plunger. 120
23. In a jar-forming machine, the combination of a mandrel of substantially rectangular cross-section, and a series of turning members working across the bottom edges of the mandrel sides and hinged together at four points corresponding to the four corner edges of the mandrel, said members having continuous operating portions which substantially meet at their ends when closed together. 125
24. In a jar-forming machine, the combination of a mandrel holder, a mandrel detachably connected therewith and having a substantially horizontal operative position, means for progressively wrapping a sheet of stock about the sides of said mandrel, and means for exerting endwise pressure against a sheet of stock applied to the vertical bottom face of said mandrel. 130
25. In a jar-forming machine, the combination of a mandrel holder pivoted to swing to operative and inoperative positions, and means for applying sheet stock to a mandrel operatively positioned on said holder to form a jar thereon. 135
26. In a jar-forming machine, the combination of a mandrel having a substantially horizontal operative position, a holder adapted to support the mandrel in said position and pivoted to swing the mandrel into an inoperative upright position, and means for applying sheet material to said mandrel. 140
27. In a jar-forming machine, the combination of a pivoted mandrel holder adapted to hold the mandrel in a substantially horizontal operative position and in a substantially upright inoperative position, a mandrel having a sliding interlocked engagement with said holder, and means for applying sheet material to said mandrel. 145
28. In a jar-forming machine, the combination of a wrapping box composed of hinged sections adapted to be extended in a substantially horizontal position, a mandrel having a horizontal operative position over 150

one of said sections, and a pivoted holder adapted to support the mandrel in said operative position and also in an upright inoperative position exposing the whole of said 5 wrapping box.

29. In a jar-forming machine, the combination of a mandrel, a pivoted holder adapted to support the same in a horizontal operative position and also adapted to swing

it upwardly into an inoperative position, 10 means for applying sheet material to the sides of said mandrel, and means for applying horizontal endwise pressure to a sheet of material on the bottom of said mandrel.

In testimony whereof I have hereunto set 15 my hand this thirteenth day of September, 1918.

JAMES H. WAGENHORST.
